TOY

Otto A. Langos, Chicago, Ill.

Application June 14, 1934, Serial No. 730,578

11 Claims. (Cl. 46—119)

My invention relates in general to toys and in particular to an animated representation of a bird.

It is well known that ordinarily an animated toy is more attractive to children than a stationary toy. A toy gun is always in favor. Combining these popular actions, I provide an animated bird mounted on a pistol-like body member and actuated by a trigger-like member on 10 said body member.

It is an object of my invention to provide an attractive, sturdy toy, susceptible of continued, hard use.

A further object is to provide such a toy, 15 which is simple, light in weight and very easy to operate, and it is also an object of my invention to provide a very inexpensive device.

Other objects and advantages of my invention will be apparent from the following description 20 taken with the drawing, in which:

Fig. 1 is a side elevation of the complete toy;

Fig. 2 is a fragmentary view partly in section of the operating mechanism of the toy, and

Fig. 3 is a perspective view of the U-shaped 25 mounting bracket.

In practicing my invention I provide a pistol-like body member for carrying in the hand, with the representation of an animated object in a toy figure pivotally mounted on the top thereof, 30 and operating mechanism carried in the body member cooperating with figure-connecting means to effect a swinging pivotal action of said figure.

Referring now to the drawing, in Fig. 1, I illustrate the complete toy of my invention with a pistol shaped body member 11 having a toy figure 12, representing a bird, pivotally mounted on the body member. The body member includes a butt-shaped handle portion 13 for holding in the hand, 40 and a hollow barrel 14 secured thereto. A removable cap 16 closes the open end of the hollow barrel 14. The barrel and handle assembly comprises more particularly a rounded chamber 17 at the top of the handle 13 having an opening 45 18 at the front thereof. The end of the barrel 14 extends into the chamber 17 as shown particularly in Fig. 2 and is spring locked therein by an indented portion 19 in the wall of the chamber 17 fitting into a corresponding aperture 21 50 in the barrel. This provides a very inexpensive and readily assembled construction for the housing which will withstand continued, and extensive abuse by a child.

The toy figure 12 is mounted on the barrel 14 55 by a pivot pin 22 extending through downwardly

extending legs 23 on the figure itself and through the barrel 14. The toy figure is moved in a swinging action from the pivot pin 22, by actuating mechanism as will be hereinafter described, operating through interconnecting means rigidly secured in the figure 12 itself.

The interconnecting means more particularly comprises a U-shaped bracket 24 as shown in Fig. 3 having outwardly extending ears 26 on each side of the upper closed portion. These ears fit 10 into slotted apertures 27 on each side of the figure 12 and are spring locked therein. The bracket 24 further includes downwardly extending legs 28 and 29 with leg 28 slightly shorter than leg 29 as shown in Fig. 2. The lower portion of each 15 of the legs is slightly offset from the remainder thereof and has a slot 31 opening upwardly from the lower edge.

Carrying out the representation of a bird in the toy figure illustrated, a swinging action of 20 the figure pivoted from the pin 22 is provided so that upon actuation of the operating mechanism the head of the bird bobs up and down in characteristic fashion. The operating mechanism cooperating with the bracket 24 in the pivotal 25 mounting heretofore described to obtain this swinging action includes a reciprocating bar 32 carried in the barrel 14 and slidably mounted over the pin 22 in an elongated aperture 33. The reciprocating bar has a toothed or serrated upper edge 34 and a downwardly extending finger-hold extension 36 protruding through a slot 37 in the bottom of the barrel. The finger-hold extension 36 resembles a trigger on a gun and is pulled backwardly in the usual manner when 35 gripping the handle 13. A spring 38 carried on the end 39 of the reciprocating bar and resting against the end of the chamber 17 acts upon the bar 32 to return it to its normal inoperative position after the movement of the trigger 36. 40 The movement of trigger 36 is limited by the ends of the slot 37.

As to the operation of the device, the bracket 24 rigidly secured in the figure 12 is positioned so that when said figure is mounted on the pivot 45 pin 22 the legs 28 and 29 extend through apertures 41 and 42 respectively and the slots 31 in the legs ride over the toothed edge 34 of the reciprocating bar. With the rear leg 29 of the bracket slightly longer than the front leg 28, the 50 figure 12 leans forwardly and when the trigger 36 is pulled to move the reciprocating bar, the figure bobs up and down as though picking up an object from the barrel 14.

Although I have described the toy figure as a 55

representation of a bird, it is understood that I may employ the likeness of any animate object, inasmuch as this action obtained with my invention will be attractive to children as applied 5 to any object. The toy as illustrated and described is simple and inexpensive both from the standpoint of cost of material and cost of assembly. It is sturdy, yet attractive as to appearance as well as operation.

10 Although I have described my invention in its preferred embodiment, it is understood that I do not limit the invention thereby, but limit it only by the scope of the appended claims.

I claim:

15 1. In an animated toy, a body member for carrying in the hand, a toy figure pivotally mounted on the body member, a reciprocating bar in said body member, and means interconnecting said bar and toy figure whereby to effect an oscillating pivotal action of said figure upon each stroke of the bar.

20 2. In an animated toy, a body member for carrying in the hand, a toy figure pivotally mounted on the body member, a spring returned reciprocating bar carried in the body member, a finger hold extension on said bar, and means interconnecting said bar and toy figure whereby upon pulling of said finger hold the bar is actuated to effect with a single stroke an oscillating pivotal action of said figure.

25 3. In an animated toy, a body member for carrying in the hand, a toy figure pivotally mounted on the body member, a spring returned reciprocating bar having a serrated upper edge

30 carried in the body member with its serrated edge above the pivotal axis of said figure, a finger hold extension on said bar, and means riding on said serrated edge of the bar and spaced lengthwise of said bar from said pivotal axis and connected to said toy figure whereby upon pulling of said finger hold said bar is actuated to effect with a single stroke an oscillating pivotal action of said figure.

35 4. In an animated toy, an actuating mechanism including a spring returned reciprocating bar having a serrated edge, a housing for said mechanism, a toy figure pivotally mounted on top of said housing, connecting means riding on said serrated edge at spaced points and extending 40 from said serrated edge through the top of said housing to said figure, and a finger hold extension on said bar extending through the bottom of said housing adapted to be pulled to move said bar to effect a swinging action of said figure 45 through the connecting means.

50 5. In an animated toy, a body member for carrying in the hand, a toy figure raised above the body member having downwardly extending legs pivotally mounted on said member, a reciprocating bar movable in said member, and means interconnecting said bar and toy figure to effect a swinging pivotal action of said figure upon actuation of the bar, said means including a U-shaped bracket having downwardly extending legs with each slotted at the end thereof and riding on said bar at the slots and with the closed end of said U-shaped bracket rigidly secured in said toy figure.

55 6. In an animated toy, a body member, a toy

figure, a stationary pivot in said body member for mounting said figure above said member, actuating mechanism in the body member and interconnecting means extending therethrough to the toy figure cooperating with said actuating mechanism to effect an oscillating pivotal action of said figure on said stationary pivot, said toy figure resembling a bird and being inclined with its head close to said body member whereby its oscillating pivotal movement makes it appear to be eating or pecking.

60 7. In an animated toy, a pistol shaped body member including a hollow barrel and butt-shaped handle, a toy figure, having downwardly extending legs, a stationary pivot pin extending through the barrel of the pistol and the legs extending downwardly on each side thereof to pivotally mount the figure on the barrel, a spring returned reciprocating bar in the barrel having an elongated aperture for fitting over said pivot pin and to slide thereon, and means interconnecting said bar and toy figure whereby to effect a swinging action of said figure on said pivot upon actuation of the bar.

65 8. In an animated toy, a body member, a toy figure pivotally mounted on the body member, an actuating member therefor movably mounted on said body member and having a serrated edge facing away from the pivotal axis of said figure, means for moving said actuating member, and means riding on said serrated edge and connected to said toy figure whereby a single movement of said actuating member effects an oscillating pivotal action of said toy figure.

70 9. In an animated toy, a body member, a toy figure pivotally mounted on the body member, an actuating member therefor movably mounted on said body member and having a smoothly curved serrated edge, means for moving said actuating member, and means riding on said serrated edge and connected to said toy figure whereby a single movement of said actuating member effects an oscillating pivotal action of said toy figure.

75 10. In an animated toy, a body member, a toy figure pivotally mounted on the body member, an actuating member therefor movably mounted on said body member and having a serrated edge, means for moving said actuating member, and means riding on said serrated edge and connected to said toy figure whereby movement of said actuating member effects an oscillating pivotal action of said toy figure, said toy figure resembling a bird and being inclined with its head close to said body member whereby its oscillating pivotal movement makes it appear to be eating or pecking.

80 11. In an animated toy, an actuating mechanism including a spring returned reciprocating bar having a smoothly curved serrated edge, a housing for said mechanism, a toy figure pivotally mounted on top of said housing, connecting means extending from said serrated edge through said housing to said figure, and a finger hold extension on said bar extending through said housing adapted to be pulled to move said bar to effect an oscillating pivotal action of said figure through the connecting means.

85 OTTO A. LANGOS.
